DESIGN FOR A WALL PLATE STAND

Carl Pinkus, New York, N. Y.

Application September 10, 1943, Serial No. 111,097

Term of patent 7 years

To all whom it may concern:

Be it known that I, Carl Pinkus, a citizen of the United States, residing at New York, in the county of New York and State of New York, have invented a new, original, and ornamental Design for a Wall Plate Stand, of which the following is a specification, reference being had to the accompanying drawing, forming a part thereof.

In the drawing:

Fig. 1 is a perspective view of a wall plate stand, showing my new design.

Fig. 2 is a front elevational view.

Fig. 3 is a rear elevational view.

Fig. 4 is a top plan view of the same.

I claim:

The ornamental design for a wall plate stand, as shown.

CARL PINKUS.
